UNITED STATES PATENT OFFICE.

FRANCIS E. MILLNER, OF MIAMI, OKLAHOMA.

RACK.

1,096,738.

Specification of Letters Patent.

Patented May 12, 1914.

Application filed July 20, 1912. Serial No. 710,605.

To all whom it may concern:

Be it known that I, FRANCIS E. MILLNER, a citizen of the United States, residing at Miami, in the county of Ottawa and State 5 of Oklahoma, have invented new and useful Improvements in Racks, of which the following is a specification.

This invention relates to racks for holding articles of merchandise, and particularly such articles as rolls of wire screen material, window shades, handles, and various other articles of a like nature, enabling said articles to be displayed to advantage and drawn therefrom as the occasion 15 may require, the rack also being adapted to contain additional supplies of such materials adapted, at any time, to be placed in engagement with the holders, hereinafter described.

With the above and other objects in view, the invention consists in the construction, combination and arrangement of parts, as will be hereinafter more fully described, illustrated in the accompanying drawings, 25 and pointed out in the claims hereunto appended.

In the drawings: Figure 1 is a side elevation of a rack, embodying the present invention. Fig. 2 is a front elevation of the 30 same, showing one pair of hooks turned into position to release one of the articles. Fig. 3 is a detail section through a portion of the rack, showing the manner of connecting the hooks thereto to admit of turning the same.

The rack contemplated in this invention comprises essentially a series of posts 1 connected by cross bars 2 and 3 extending at right angles to each other, and permanently 40 fastened at their ends to said posts, any desired number of such cross bars being employed at the top and bottom, and intermediate points of the corner posts to produce a sufficiently rigid frame, for the purpose 45 hereinafter specifically pointed out. The intermediate cross bars, indicated at 4, may be used as extra supports for stock rolls of material, as shown, while a common supporting base 5, to which all of the corner 50 posts are connected, forms a support for other rolls of material, the base being provided with a suitable number of supporting rollers or caster wheels 6 to enable the same to be readily rolled from place to place.

The main feature of the present invention 55 resides in connecting with the corner posts 1 a number of sets of holders 7, each set of holders embodying two L-shaped hooks 7. These hooks are of sufficient size to embrace the rolls of material, indicated at 8, as 60 shown in Fig. 1, the shank portions of the hooks passing through holes bored horizontally through the corner posts 1, it being preferred to thread the shank portions of the hooks and secure the same in place relative 65 to the corner posts by placing nuts 9 thereon at opposite sides of the posts. The end portions of the hooks extend downwardly, as clearly shown in Fig. 1, so as to embrace the roll or article resting on the pair of hooks 70 next below the ones referred to. It will now be seen that by turning any pair of hooks from a vertical to a horizontal position, the roll previously retained in position thereby is free to be readily removed and replaced. It 75 will further be seen that to remove a certain article or roll of material, it is not necessary to disturb any of the other articles, which remain in their respective places until needed.

The rack as a whole, hereinabove described, and illustrated in the accompanying drawings, will be found of the greatest possible convenience in practice, and will save much valuable time, as well as keep the rolls of 85 material or other articles in excellent condition.

What is claimed is:

1. A rack for the purpose specified, comprising a frame, a plurality of sets of holders projecting therefrom, each set embodying a pair of L-shaped supporting and retaining hooks arranged in the same horizontal plane and having their horizontal members journaled in the frame in such 90 manner as to adapt the free vertical members thereof to be turned in a substantially vertical plane to hold and release the object held thereby, one set of holders being so combined with and related to the adjacent 95 100 set that the object supported by one set is retained on these holders by the adjacent set.

2. A rack for the purpose specified, comprising a frame, a plurality of sets of holders projecting therefrom, each set embodying a pair of L-shaped supporting and retaining hooks arranged in the same horizontal plane and having their horizontal mem- 105

bers journaled in the frame in such manner as to adapt the free vertical members thereof to be turned in a substantially vertical plane to hold and release the object held thereby, the hooks of one set being arranged above those of the adjoining set in such relation that the vertical members of one set act as retainers for the article supported

by the horizontal members of the next lower set.

In testimony whereof I affix my signature in presence of two witnesses.

FRANCIS E. MILLNER.
